(57) **CLAIM**

The new, original, and ornamental design for a miniature space weapon, as shown in FIGS. 1-7.

DESCRIPTION

FIG. 1 is a perspective view of a miniature space weapon according to my new design.

FIG. 2 is a front view of the miniature space weapon of FIG. 1.

FIG. 3 is a rear view of the miniature space weapon of FIGS. 1-2.

FIG. 4 is a top view of the miniature space weapon of FIGS. 1-3.

FIG. 5 is a left side view of the miniature space weapon of FIGS. 1-4.

FIG. 6 is a right side view of the miniature space weapon of FIGS. 1-5; and,

FIG. 7 is a bottom view of the miniature space weapon of FIGS. 1-6.

The design of the present invention and as shown in FIGS. 1-7 is an ornamental, miniature space weapon that is compatible with miniature space action figure toys.
